DESIGN FOR A SHOE SOLE

Maurice J. Bernstein, Brighton, Mass., assignor
to Panther-Fanco Rubber Co. Inc., Chelsea,
Mass., a corporation of Massachusetts

Application November 14, 1935, Serial No. 59,565

Term of patent 14 years

To all whom it may concern:

Be it known that I, Maurice J. Bernstein, a citizen of the United States, residing at Brighton, in the county of Suffolk and Commonwealth of Massachusetts, have invented a new, original, and ornamental Design for a Shoe Sole, of which the following is a specification, reference being had to the accompanying drawing, forming a part thereof.

In the accompanying drawing there is shown a bottom plan view of a shoe sole of conventional thickness and of molded composition, the domi-

nant feature of which is the raised or embossed ornamented area extending about the margin of the shoe sole at the tread face, and separated from the inner flat surface of the shoe sole by an embossed rib, the ornamented margin and defining rib being exposed on the lower or tread face of the sole when incorporated in a shoe.

I claim:

The ornamental design for a shoe sole substantially as shown and described.

MAURICE J. BERNSTEIN.
